UNITED STATES PATENT OFFICE.

MATTHEW CLARKE, OF WILKES-BARRE, PENNSYLVANIA.

ELLIPSOGRAPH.

1,264,157.

Specification of Letters Patent. Patented Apr. 30, 1918.

Application filed July 31, 1917. Serial No. 183,698.

To all whom it may concern:

Be it known that I, MATTHEW CLARKE, a citizen of the United States, residing at Wilkes-Barre, in the county of Luzerne and State of Pennsylvania, have invented certain new and useful Improvements in Ellipsographs, of which the following is a specification.

My invention relates to new and useful improvements in drafting instruments and more particularly to instruments of the type known as ellipsographs, the primary object of my invention being the provision of an instrument by means of which ellipses may be quickly and correctly drawn.

Although my drafting instrument is primarily intended for drawing ellipses, a further object of my invention resides in so constructing it that it may be employed in drawing ovals, circles, semi-circles and quarter-circles, and also straight lines.

Another object which I have in view is the provision of an instrument of this character which may be employed with equal facility for inscribing the various figures either upon a horizontal or a vertical surface.

Another object which I have in view is the construction of the device in such a manner that it may be folded into relatively compact space when not in use.

With these and other objects in view, my invention will be more fully described, illustrated in the accompanying drawings, and then specifically pointed out in the claims which are attached and form a part of this application.

In the drawings:

Figure 1 is a perspective view of my improved drawing instrument showing the method of employing it in drawing ellipses.

Fig. 2 is a plan view of the mechanism showing the position of the parts when the drawing of an ellipse is to be started.

Fig. 3 is a plan view, parts being broken away, showing the employment of the device for drawing semi-circles.

Fig. 4 is a plan view illustrating how a portion of the device may be separately employed for inscribing circles or arcs of circles.

Fig. 5 is a fragmentary sectional view taken on the line 5—5 of Fig. 3 looking in the direction of the arrows.

Fig. 6 is a section taken on the line 6—6

of the same figure, also looking in the direction of the arrows.

Fig. 7 is a section taken on the line 7—7 of Fig. 2 looking in the direction of the arrows.

Fig. 8 is a section taken on the line 8—8 of Fig. 2 looking in the direction of the arrows.

Fig. 9 is an unassembled perspective view of the marker holder.

Fig. 10 is a view illustrating various figures which may be readily drawn with my drafting instrument.

Corresponding and like parts are referred to in the following description and indicated in all the views of the drawings by the same reference characters.

Broadly speaking, my drafting instrument includes mutually adjustable bars or slideways 11 and 12, and a marker carrying arm 13 having sliding and swinging engagement with the slideways but detachable therefrom. The device may be formed largely of wood but is preferably formed of metal of suitable quality and weight. The slideway 11 is in the form of a rectangular strip of metal having its ends bent downwardly at right angles to the body to form supporting legs 14 terminating in outwardly or laterally directed supporting feet 15, the under surfaces of which may be provided with non-slipping cushions 16 of felt or rubber, if desired. The strip adjacent its supporting legs is preferably pointed or tapered, as shown, for a reason which will be later apparent, and the strip throughout its entire length from one supporting foot to the other is provided with a medial longitudinal guide slot 17.

The slideway 12 includes a rectangular strip of metal or other suitable material provided along one side with an upstanding longitudinal flange 18 and at its ends with downwardly directed supporting legs 19 having feet 20 provided, if desired, with non-slipping cushions 21. The supporting legs 19 are so proportioned with respect to the supporting legs 14 that when the slideway 12 is positioned upon the slideway 11, all four of the feet of the slideways will uniformly engage against a plane surface such as a drawing board. A slot 22 is formed at the juncture of the flange 18 and body of the slideway 12, extending from ad-

5 jacent one end of the flange to a point adjacent the opposite end. These slideways may be made in any desired size but preferably the slideway 12 is considerably longer than the slideway 11.

10 A clamp 23 is adjustably and slidably mounted upon the slideway 11 and includes a body portion 24 engaging against the under face of the slideway and upwardly and inwardly directed retaining flanges 25 engaging against the side edges and over the upper face of the slideway with their free edges disposed in parallel spaced relation to each other, as clearly shown in Fig. 1 15 of the drawings. The intermediate portion of the slideway 12 at its side edge opposite the flange 18 is provided with a laterally directed tongue 26 adapted, when the slideway 12 is disposed across the slideway 11 20 and at right angles thereto, to seat snugly between the ends of the flanges 25, and a clamping screw 27 having a milled head for convenience of adjustment, is passed through an opening formed in this tongue 25 and threaded into and through an opening formed in the body portion 24 of the clamp 23. By this means the slideway 12 may be constantly held at right angles to the slideway 11 with its intermediate portion 30 over such slideway and may be adjusted from end to end of the slideway 11 as desired. A bracing arm 28 in the form of a tongue extended from the intermediate portion of the upper edge of the flange 18 35 has its end bent downwardly and riveted or otherwise secured, as shown at 29, to the tongue 26 to brace the flange portion 18 with respect to the body of the slideway 12. Furthermore, the tongue 26 is formed 40 of such length that by loosening the clamping screw 27 to permit raising of the tongue between the flanges 25 the slideway 18 may be swung to extend parallel to the slideway 11 and tilted somewhat to bring the free 45 end of the tongue 26 into snug engagement against one of the flanges 25 when the screw 27 may be again tightened to hold the parts together. Because of this these two parts may be locked in a position to occupy but 50 little space when the instrument is not in use.

Coöperating with the slideway 12 is a carriage or slide 30 including a rectangular body extending at right angles to the slideway and disposed for sliding movement within the slot 22 thereof. This body at each side is provided with lateral extensions 31 formed at their ends with upwardly directed tongues 32 which engage against 55 opposite faces of the flange 18 to hold the slide or carriage in the slot, against any swinging or tilting movement and to at the same time leave it free for sliding movement along the slot. That end of the slide 60 or carriage 30 not resting upon the body of

the slideway is formed with an upwardly extending curved hook 33 the bill of which is directed back toward the flange 18, as best shown in Fig. 7 of the drawings. Pivoted to the flange 18 is a hasp or latch 34 70 having in its lower edge a notch 35 capable of seating over one of the tongues 32 of the carriage 30 when the latch is in active position, so that the carriage may be locked to the slideway 12 near the intermediate portion of such slideway when circles are to be described. This latch has a laterally directed finger piece 36 by means of which it may be shifted. When the latch is inactive, the finger piece will rest upon the upper edge of the flange 18, as shown in Figs. 1 and 2, to support the latch out of the path of the slide 30.

75 The above described structure constitutes the main body or frame work of my drawing instrument and coöperating with it is the swinging arm 13 in the form of a rectangular strip of sheet metal or other suitable material provided adjacent one end and centrally of its width with an opening 80 37 by means of which it may be swingingly connected with the hook 33. This arm has its ends mounted as shown and is provided throughout its length and centrally of its width with a longitudinal slot 38. The arm 90 95 at one side of the slot is marked or graduated with scale divisions, in inches or other suitable standards of length, as indicated at 39, the zero of this scale being coincident with the center of the pivot opening 37 of 100 the arm. A sliding clamp 40 identical in construction with the clamp 23 with the exception that one of its flanges is cut away centrally of its length as shown at 41, to provide an indicating finger for coöperation 105 with the scale, is mounted upon the arm 13. The clamping screw 42 coöperating with this clamp has an annular shoulder 43 for engagement with the upper face of the arm 13, a smooth intermediate shank section fitting snugly within the slot 38, and a pointed or pronged terminal 44, the smooth shank section being also proportioned to fit snugly 110 within the slot 17 of the slideway 11. As will be readily apparent by reference to 115 Fig. 1, the arm 13 has sliding swinging engagement at whatsoever point the clamping screw 42 is located, with the slideway 11. It should be noted that the indicating finger or shoulder 41 is directly in line with the 120 axis of the clamping screw 42 so that an exact setting of this clamping screw with respect to the scale may be readily accomplished.

125 Also slidably mounted upon the arm 13 is a pencil carrier indicated as a whole by the numeral 45. This carrier includes a sliding clamp 46 identical in construction with the sliding clamps 23 and 40, with the exception that that flange overlying the scaled portion 130

of the arm 13 is provided at that edge nearer the pivoted end of the arm with a laterally directed indicating finger or extension 47. A supporting bracket 48 has at its lower end 5 a laterally directed foot 49 proportioned to fit snugly between the inner edges of the flanges of the clamp 46 and to rest upon the upper face of the arm 13, and a clamping screw 50 is passed through this foot and 10 threaded through the intermediate portion of the body of the clamp 46. The upper end of the bracket 48 is formed with a lateral pencil supporting extension 51 which extends in parallel spaced relation above the 15 arm 13 with its free end directed toward the pivoted end of such arm and with its inner face in vertical alinement with that side of the slot 38 remote from the scale 39. This extension is formed intermediate its length 20 with a vertically disposed pencil receiving seat 52 and at either side of the seat with openings 53 to receive the arms of a U-shaped clamping bolt 54, the intermediate portion of which is adapted to engage about 25 a pencil 55 engaged in the seat. One of these arms is proportioned to lie practically wholly within the extension 51 while the other, which is longer, is threaded to receive a clamping nut 56, by means of which the 30 pencil may be clamped in place so that it will project through the slot 38 with its lower pointed end in position to rest upon a sheet of paper or other surface to be inscribed when the slideways rest against such 35 surface.

As previously pointed out, the above described instrument is primarily intended for use in drawing or inscribing ellipses and in Figs. 1 and 2 of the drawings I have illustrated the manner of employing it for this purpose. Assuming that the parts are in the position shown in Fig. 2 with the screw 42 engaging the slot 17 of the slideway 11 and with the arm 13 engaging against the 40 flange 18, it will be clear that the point of the pencil, the axis of the screw 42 and the axis of the pivot opening 37 of the arm lie in a common plane parallel to the flange 18. If then, the pencil is grasped and the arm is 45 swung from its initial position in the direction of the arrows shown in Fig. 1, the slide 30 will move along the slot 22 of the slideway 12 toward the intermediate portion of such slideway while the screw 42 will slide 50 along the slot 17 away from the slideway 12 until the pencil has passed the end of the slideway 11, when further movement of the pencil will cause continued movement of the slide 30 in the same direction but reverse 55 movement of the screw 42 along the slot 17 until the arm again engages against the flange 18 but at the opposite side of the slideway 11. This movement of the pencil will have inscribed a semi-ellipse, the major 60 axis of which is in alinement with the slot 65 17 of the slideway 11. By then reversing the position of the instrument and bringing the pencil to original position with its point at one end of the semi-ellipse, the pencil may be again swung in the same manner to complete the ellipse. 70

By proper relative adjustments of the clamp 40 and pencil holder 45 ellipses having major and minor axes of any desired length within the range of the instrument 75 may be drawn. Furthermore, the length of the major axis of the ellipse with respect to the length of the minor axis thereof may be varied at will by suitable adjustment of these parts. For instance, as shown in Figs. 80 1 and 2 of the drawings, the instrument is set with the pencil at the figure nine in the division of the scale, that is at nine inches from the hook 37 about which the arm 13 swings, so that the major axis of the ellipse 85 will be eighteen inches. The screw 42 which controls the length of the minor axis of the ellipse is set at the three and a half inch division of the scale or, in other words, at five and a half inches from the pencil so that 90 obviously the minor axis of the ellipse will be eleven inches. The manner of adjusting these parts to get ellipses of various sizes and proportions will be readily apparent from this single example. For instance, in 95 Fig. 10 I have illustrated ellipses *a*, *b* and *c* of various sizes and proportions such as may be drawn with my instrument. Obviously, the sliding clamp 25 connecting the slide 100 ways 11 and 12 should be adjusted longitudinally of the slide way 11 in such a manner that irrespective of the relative settings of the pencil and guide screw 42, the guide screw 42 may always remain in the slot 17 and the pencil may always be free to pass 105 about the end of the slide way 11. In other words, if relatively smaller ellipses are to be drawn, the slide way 12 will be clamped to the slide way 11 with its flange 18 relatively close to the adjacent end of the slide way 11. 110 Rounding of the ends of the slide way 11 facilitates the passage of the pencil about it when the pencil is located very close to the guide screw 42.

Obviously, the above described instrument 115 may be employed for drawing semi-circles by locking the slide or carriage 30 by means of the hasp 34, freeing the guide screw 42 from the slot 17, either by completely removing it or by moving it and its clamp to 120 a remote portion of the scale, and by then starting with the arm against the flange 18, swinging the pencil about the hook 37 as a pivot until the arm again engages the flange. 125 Obviously, an exact half-circle will thus be 130 inscribed and no protractors or other instruments are necessary to measure the arc of such circle. Obviously also, quarter circles may be readily drawn by so adjusting the two slide ways that movement of the pencil

in the same manner as set forth in drawing a semi-circle, will bring it into engagement with the slide way 11, as when the slide 30 is locked the axis of the hook is disposed at 5 one side of the slide way 11 at such distance that when the pencil engages the slide way its axis or point will lie in a common plane with the axis of the hook at right angles to the slide way 12.

- 10 Obviously, the free ends of a semi-ellipse may be connected by the free ends of a semi-circle having a diameter equal to the minor axis of the semi-ellipse to produce an oval, as shown at *d* in Fig. 10, this figure also 15 illustrating a semi-circle at *e*, a circle at *f*, and a crescent at *g*, all of which may be drawn by proper manipulation of the instrument. Although a circle may be drawn by inscribing a half-circle, reversing the instrument and inscribing the supplemental 20 half of the circle, the preferred way of employing the instrument for this purpose is by freeing the arm 13 from the hook, removing the clamping screw 42, sliding the 25 clamp 40 to bring its threaded opening in alinement with the opening 37 of the arm 13, replacing the clamping screw, adjusting the pencil along the arm 13 to the point of the scale in the desired radius of the circle, 30 placing the point of the clamping screw 42 against the surface upon which the circle is to be drawn, and then swinging the pencil about the screw as a center. Absolute accuracy in the size of the circle is obtained 35 by this method as the scale is calibrated from the center of the opening 36 and the pencil is set by the scale.
- Obviously, the pencil may be replaced by a suitable pen, a slate pencil, a crayon, or 40 by a pointed metallic marker, as desired, according to the type of work to be done or the surface to be inscribed. Because of this and because of the possibilities of varying the construction and size of the various 45 clamps and slides and the size and proportions of the parts, it will, of course, be apparent that the invention is not restricted to the specific details of construction illustrated and described but changes may be 50 made within the scope of the appended claims. Furthermore, it will be clear that by removing the arm 13 from the supporting frame and by removing the pencil holder and clamp 40 from the arm, this arm may 55 be employed as a rule or straight edge. Again, with the slide ways clamped in the position shown in Figs. 1 and 2, and the arm removed, these slide ways may be used as a try-square. When the instrument is 60 not in use the slide ways may be clamped in parallel relation to each other, the clamp 23 being so adjusted upon the slide way 11 that the ends of the latter slide way will not project beyond those of the other and 65 the swinging arm may be unhooked and

disposed parallel to the slide ways. Under these circumstances the device will occupy but little space for storage or shipment. The arm may be made in any desired length but the slide way 11 should vary in length to 70 correspond thereto, being preferably several inches longer than one-half the length of the arm in order to give proper range to the instrument.

Having thus described the invention, what 75 is claimed as new is:

1. A drawing instrument including supporting members each adjustable longitudinally of the other, means for securing said members together, a marker arm having a 80 slidable and pivotal engagement at one end with one supporting member and having slidable engagement intermediate its ends with the other supporting member, and a marker carried by the free portion of said 85 arm.

2. A drawing instrument comprising a support, a marker arm for pivotal and slidable connection with the support, a bracket carried by said arm and adjustable longitudinally of the same, said bracket having an overhanging arm disposed longitudinally of the marker arm and provided with a seat in its side, and a marker adjustably secured 90 in said seat.

3. A drawing instrument including supporting members formed with longitudinal slots, means for adjustably clamping one supporting member across the other to extend at right angles thereto, an arm, a marker holder adjustable longitudinally of the arm, means carried by the arm and having sliding engagement in one of the slots, and means pivoted to one end of the arm and having sliding engagement with the other 100 slot.

4. A drawing instrument including supporting members formed with longitudinal slots, means for adjustably clamping one supporting member across the other to extend at right angles thereto, an arm, a marker holder adjustable longitudinally of the arm, means carried by the arm and having sliding engagement in one of the slots, and means pivoted to one end of the arm and having sliding engagement with the other 110 slot, the first mentioned means being adjustable longitudinally of the arm.

5. A drawing instrument including supporting members formed with longitudinal 120 slots, means for adjustably clamping one supporting member across the other to extend at right angles thereto, an arm, a marker holder adjustable longitudinally of the arm, means carried by the arm and having sliding engagement in one of the slots, means pivoted to one end of the arm and having sliding engagement with the other slot, the first mentioned means being adjustable 125 longitudinally of the arm, and means for lock- 130

ing the last mentioned means against movement in its slot.

6. A drawing instrument including supporting members provided at their ends with depending feet whereby one member may be supported across and in engagement with the other member and the other member supported above a surface to be drawn upon, means carried by one of the members 10 for adjustably securing the members together and at right angles to each other, one of the members being formed with a longitudinal slot, a longitudinal slotted flange projecting upwardly from the other member, 15 a slide movable in the latter slot, a scaled longitudinally slotted arm pivoted at one end of the slide, a slide adjustably clamped to the arm and having a portion adapted to project through the slide of the 20 unflanged member, and a marker holder adjustable along the arm and adapted to be clamped thereto.

7. A drawing instrument including a longitudinally slotted supporting member hav-

ing depending supporting feet, a clamping 25 element engaged partially about the member with flanges opposed to each other and spaced at either side of the slot, a second supporting member provided intermediate its length with a laterally directed tongue 30 adapted to fit snugly between the flanges, a clamping screw passed through the tongue and slot and threaded into the clamping member to adjustably clamp the supporting members at right angles to each other, the 35 second supporting member having depending feet, an upwardly directed longitudinally slotted flange carried by the second supporting member, an arm having swinging and sliding engagement with the second 40 supporting member, means having slidable engagement with the first supporting member adjustably mounted upon the arm, and means for supporting a marker element upon the arm. 45

In testimony whereof I affix my signature.
